UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

CHARGING VERTICAL RETORTS

Application filed June 27, 1925. Serial No. 40,068.

This invention comprehends improvements of general utility in the coking retort and kindred arts, and in its more specific aspects relates to improvements in retorts of the continuous vertical type as exemplified, for instance, in my application—Serial No. 684,342, filed January 4, 1924, and has for an object the provision of means for efficiently transferring the material to be coked from a source of supply to the coking chambers of a battery of retorts.

Where a continuous vertical retort battery comprises retorts and heating wall units separated by wall structure of considerable thickness the problem of providing charging apparatus therefor with adequate supports is simplified since the supporting columns can be located within said separating walls, but where, as herein contemplated, such walls are dispensed with and a long battery of continuous vertical retorts comprising ovens and heating walls juxtaposed in alternation is employed the difficulties of charging are materially increased. An outer framework can not be used for the support of the storage bins because not only is the top of such a battery very high but the bins would have to be elevated considerably above the top to provide the head room essential for operating a battery of this type. An outer framework for a structure of this height would therefore necessitate the use of diagonal wind bracing but the length and height of the battery precludes the use of the necessary bracing of this type. Moreover, the fire hazards incident to the location of storage bins above such retorts is an additional important objection to their use.

My invention involves, broadly, the idea of practical means for overcoming all of these obstacles whereby a continuous vertical retort battery, without regard to its length or height, may be efficiently equipped with charging apparatus. In the more specific aspects of my invention, I provide a charging larry car and a trackway therefor, the trackway being preferably supported on a framework independent of the brickwork and preferably above stationary charging hoppers for the several retorts, said charging hoppers be-

ing in turn preferably elevated above the normal level of the brickwork. The larry car is preferably provided with a hopper adapted to receive the coal from the storage bin and discharge the same into the respective feed hoppers, the larry car hopper preferably extending below the body of the car and between and to a point below the tracks so that when it is in alignment with a stationary feed hopper a clear view of their relationship is afforded. Inspection may be further facilitated by the provision of an operator's platform on the larry car likewise extending below the car body and between and below the rails in proximity to the larry car hopper. To further facilitate inspection of the discharging operations the lower end of the larry car hopper is offset and in order to prevent spillage of the fuel is provided with a pipe which may be dropped to span the space between said larry car and said stationary feed hopper. This pipe is preferably adapted to be extended to a point in the feed opening sufficiently low to permit, when removed, the closing of the feed opening without obstruction by the material in said opening and a valve is also preferably provided between the hopper body proper and said pipe to control the flow of material to the latter.

As a further specific aspect of my invention, a storage bin, preferably supported independently of the battery brickwork and preferably separated from the battery structure proper, is employed. This removes the bin from fire hazards and enables its supporting structure to be adequately braced against wind pressure and other disturbing forces which is desirable because of the great height to which continuous vertical retorts are built.

In addition to the general features and objects of the invention above recited, the invention has such other improvements or advantages in construction and operation as are found to obtain in the structure and devices hereinafter described or claimed.

In the accompanying drawings, forming a part of this specification, and showing for purposes of exemplification, a preferred form and manner in which the invention

may be embodied and practiced, but without limiting the claimed invention specifically to such illustrative instance or instances:

Figure 1 is a vertical longitudinal section 5 on the line 1—1 of Fig. 2, showing a portion of a continuous vertical retort battery and a storage bin and supported structure therefor, the two structures being connected by a trackway on which a larry car is adapted to travel 10 carrying with it a fuel conveying hopper,

Fig. 2 is a vertical transverse section 15 through the battery, showing the relationship between the coking chambers, stationary feed hoppers, larry car charging device, and rails and supporting structures for the same, and

Fig. 3 is a detail sectional view of the lower 20 end of the larry car hopper showing a pipe adapted to be lowered to bridge the space between said hopper and the stationary 25 charging hopper.

The same characters of reference indicate the same parts in each of the several views of the drawings.

Referring to Fig. 1 of the drawings, there 25 is shown a supporting structure or tower 1 having near its top a storage bin 2 which is adapted to be filled with fuel by suitable transfer means from a main source of supply, such, for example, as a barge or freight car. The top portion of a vertical retort is shown at 3 having coking chambers 4 separated by heating walls 5, said chambers being provided at their tops with stationary charging 30 hoppers 6 rising above the top of the brickwork and adapted to be substantially filled with the fuel and to deliver the same continuously to the coking chamber. A supporting framework on the exterior of the brickwork 35 is shown at 7 which framework may carry at its top a superstructure or housing 8 adapted to support the trolley conductors 9 and a trackway 10, the rails of which are separated by a free space longitudinally of the battery 40 and above the stationary feed hoppers. A larry car 15, provided with a fuel conveying 45 hopper 16 having at its lower extremity an offset discharge valve mechanism 17, is adapted to travel on the trackway. The discharge end of the larry car hopper extends 50 below the body of the larry car proper and through the space between the rails so that when the lower offset end of the hopper is in vertical alignment with a stationary hopper 55 the discharge outlet of the former will be over the charging opening of the latter. Said larry car is also provided with an operator's platform 25 likewise extending through said space between the rails in proximity to the lower end of the larry car hopper. The valve mechanism comprises a pipe 18 with its upper side portion cut away at 60 19 as shown in Fig. 3, said pipe being adapted to slide in the guide portion 20 of the car hopper and to be substantially balanced in

raised or lowered position by the lever 21, counterweighted at 22. A fuel valve 23 operated by lever mechanism 24 controls the flow of fuel from the car hopper. When the valve 23 is opened and the pipe 18 lowered the cut away portion 19 of the latter permits flow of the fuel from the car hopper 16 to the charging hopper 6 while the pipe bridges the space between said hoppers and thereby prevents spillage of the fuel.

In the operation of the device, when it is desired to charge the stationary hoppers, the larry car is run to a position beneath the storage bin and charged with fuel, its capacity being sufficient to enable it to charge a 30 plurality of ovens. The car 15 is then run to a position with the discharge valve 17 vertically above the stationary charging hopper 6 which it is desired to fill. The anti-spillage pipe 18 is then dropped into position to bridge the space between the car hopper extension and the feed opening in the stationary hopper, extending downwardly into the latter, the pipe being maintained in the adjusted position by the counterweight 35 22. The valve 23 is then opened and the material flows from the hopper, through the pipe and into the stationary charging hopper.

The operator, from his position on the platform, may observe the proper alignment of the parts as well as the feeding operation. By the arrangement disclosed the spillage of fuel is rendered impossible since when the stationary hopper is filled the downward flow of fuel will stop inasmuch as it passes through a passageway entirely closed laterally by the sides of the hopper and the interconnecting pipe. When the charging operation is completed the valve is closed and the pipe lifted, the material settling to a point 40 sufficiently below the top of the feed opening in the stationary hopper to permit the cover to be placed thereon. This results from the fact that in the charging position the end of the pipe extends substantially below the top of the feed opening, leaving a space above the lower end of the pipe sufficient to accommodate the charge remaining in the pipe after the valve is closed. This provision is of great importance in continuous vertical retorts in which the feeding operation is continued until the stationary hopper is filled and no space in the body of the hopper remains for the contents of the pipe when withdrawn. The same problem is not met with in ovens of the horizontal type since the latter are never completely filled. After the charging operation is completed the larry car is free to move on to the next stationary hopper to be charged, and similarly for the remainder of the stationary hoppers.

The invention as hereinabove set forth is embodied in a particular form of construction, but may be variously embodied within the scope of the claims hereinafter made.

I claim:

1. In a vertical retort battery, or the like, in combination: a larry car provided with a charging hopper adapted to discharge fuel into a retort chamber, said hopper being provided at its lower extremity with an offset discharge member provided with a valve controlling the flow of the fuel, said member being adapted to be positioned over the feed opening in the retort chamber to provide a view of the charging operation unobstructed by the body of the hopper; and an operator's platform carried by the larry car adjacent said offset discharge member substantially as specified.
- 15 2. In a vertical retort battery, or the like, in combination: a movable charging hopper adapted to discharge fuel into a retort chamber, said hopper being provided at its lower extremity with an offset discharge outlet adapted to be positioned over the feed opening in the retort chamber to provide a view of the charging operation unobstructed by the body of the hopper; and an operator's platform movable with said charging hopper and located adjacent said off-set discharge outlet substantially as specified.
- 20 3. In a coke oven, or the like, provided with heat treating chambers and feed openings therefor, in combination: a charging device provided with a hopper having its lower or discharge end offset; means carried by said offset to control the flow of the material and other means carried by said offset end movable to bridge the space between said end and one of said chamber feed openings to prevent spillage; substantially as specified.
- 25 4. In a coke oven, or the like, provided with heat treating chambers and feed openings therefor, in combination: a charging device provided with a hopper having a discharge outlet; means carried by said device and movable to bridge the space between said discharge outlet and one of said chamber feed openings to prevent spillage; and a valve between the feed hopper proper and the means for preventing spillage to cooperate with the latter in charging and in discontinuing the charging operation, said bridging means and valve being both offset from the lower discharge end of the hopper; substantially as specified.
- 30 5. In a coke oven, or the like, provided with heat treating chambers and feed openings therefor, in combination: a charging device adapted to deliver the charging material to said chambers; and means carried by said device and movable to bridge the space between said device and one of said feed openings; and a counter weight for said means to maintain it in feeding or in non-feeding position; substantially as specified.

In testimony whereof, I have hereunto set my hand.
